CLAIM

We claim the ornamental design for a bottle, as shown and described.

DESCRIPTION

FIG. 1 is a front perspective view of a bottle;

FIG. 2 is a front elevation view thereof, shown at an enlarged scale;

FIG. 3 is a right side elevation view thereof, the left side elevation view being identical;

FIG. 4 is a top plan view thereof; and,

FIG. 5 is a bottom plan view thereof.

The ornamental design for the bottle which is claimed is shown in solid lines in the drawings. The broken lines shown in the drawings are for illustrative purposes only and form no part of the claimed design.

The broken lines shown in the drawings are for illustrative purposes only and form no part of the claimed design.
